Primary Examiner — David Muller*Assistant Examiner* — Nathan Johnston(74) *Attorney, Agent, or Firm* — Gardner Groff Greenwald & Villanueva, PC(57) **CLAIM**

The ornamental design for a male enteral coupling, as shown and described.

DESCRIPTION

FIG. 1 is a perspective view of a male enteral coupling according to our new design.

FIG. 2 is a second perspective view thereof.

FIG. 3 is a first side elevation view thereof.

FIG. 4 is a second side elevation view thereof.

FIG. 5 is a first end view thereof.

FIG. 6 is a second end view thereof.

FIG. 7 is a top plan view thereof; and,

FIG. 8 is a bottom plan view thereof.

The broken line showing of male enteral coupling is included for the purpose of illustrating portions of the "article" and forms no part of the claimed design.
